EXPANSION-TYPE GRAPPLE FOR LIFTING AND CARRYING LOADS

John Morrow, Jr., 224 S. Michigan Ave., Chicago, Ill.
Filed Dec. 13, 1960, Ser. No. 75,559
1 Claim. (Cl. 294—97)

This invention relates to lifting and carrying grapples and more specifically to such grapples of the expanding type.

An important object of the invention is to provide an expanding type grapple which is adapted to adjust itself automatically for the support and carrying of loads, either stacked or unstacked, having openings of various shapes, such as pneumatic and other tires, window frames, sewer pipe sections whether circular or oval walled in transverse section, and belled at the ends or not, wheel rims, coils of wire or other rope, preformed building trusses and the like.

Another important object is to provide an expanding type grapple provided with a plurality of support legs, as more than two and preferably three, so that there will be at least a three-point suspension of the load by the grapple, whereby the load will not be apt to tip, even if the grapple legs do not contact the walls of the opening in the load.

Still another important object is to provide an expanding type grapple which is of sturdy construction, contains no complicated mechanisms or parts which require complex adjustments, may be manufactured at low cost, since there is no detailed machining of parts, and a shop equipped with a conventional shear, punch press, hack or like sawing means, and welding equipment can manufacture the grapple.

Furthermore, an important object is to provide an expansion-type grapple which immediately and automatically centers its arms on lifting and there is coordinated retraction of the arms for easy entry and withdrawal from the load without binding or dragging actions of the grapple.

Additionally, an important object is to provide an expansion-type grapple which will automatically adjust itself to the openings in separate piles or stacks of loads, even though the separate piles or loads may vary as to the diameters of the openings. The grapple of this invention does not require to expand to its maximum limit in order to lift and carry a load.

Other objects and advantages of the invention will be apparent during the course of the following detailed description of the invention, taken in connection with the accompanying drawings, forming portions of this disclosure, and in which drawings:

FIG. 1 is a perspective view of one form of the invention, with the grapple in a collapsed position (in full lines) and in one expanded position (in dash lines).

FIG. 2 is a top plan view of the grapple of FIG. 1.

FIG. 3 is a horizontal transverse sectional view, substantially on the line 3—3 of FIG. 1.

FIG. 4 is a vertical sectional view of the lower portion of the grapple of FIGS. 1-3, in expanded grappling connection with a stacked load, shown in vertical section.

FIG. 5 is a vertical sectional view of the grapple of FIGS. 1-4 engaging a support upon which is a stacked load, spaced from the grapple.

FIG. 6 is a perspective view of the upper end portion of a reciprocable tubular body member of the grapple of FIGS. 1-5.

FIG. 7 is a horizontal transverse sectional view of the upper end portion of the member of FIG. 6 with the first coupling means attached thereto and shown in horizontal section.

FIG. 8 is an elevational view of a sleeve reciprocable

2

member of the grapple, with second coupling means attached thereto.

FIG. 9 is an elevational view of the upper end portions of a modified form of the grapple.

5 FIG. 10 is a horizontal transverse sectional view of the elements of FIG. 9, substantially on the line 10—10 of FIG. 9.

In the drawings wherein for the purpose of illustration are shown two forms of the invention, and wherein 10 similar reference characters designate corresponding parts throughout the several views, the letters A and B designate respectively two forms of the invention, C and D two examples of loads and E a load support.

The two forms A and B of the invention are preferably 15 exactly alike except for one of the coupling means, as will be more fully detailed.

The grapple of form A of the invention includes an upwardly-extending tubular body member 15 which is shown as an elongate sleeve, which may be of iron or 20 steel or of other metal or alloy, but preferably of steel, open at its upper end portion 16 (FIG. 6) which is preferably provided with a pair of short diametrically-opposite longitudinally-extending slots 17 for connection, at the walls thereof, with first coupling means 50, to 25 be described. Projecting outwardly from the outer periphery of the end portion 16 is a stop means 18, which is preferably a lug and may be attached to the end portion 16 by providing an outwardly-opening screw threaded socket 19 in the portion 16 to receive a conventionally 30 exteriorly screw-threaded portion of the lug.

The member 15 also fixedly carries a plurality of first and second projections, as spaced-apart pairs of ears 20 and 21, comprising pairs of first ears 20 rigid with and extending radially outwardly from the outer periphery 35 of the member 15 and spaced well below the stop means 18 as, for example, about one-third the length of the member 15 from the top edge thereof. Preferably, at the lower end portion of the member 15 are a plurality of pairs of spaced apart second projections as the second 40 ears 21 rigid with and extending radially outwardly from the outer periphery of the member 15 and disposed with their upper edges or faces facing the lower edges or faces of the ears 20. I prefer to provide three pairs of ears 20 and 21, although there may be more than 45 three pairs each. Each ear is provided with an axially-aligning horizontally extending bore or opening to receive pivot means such as the shanks of bolts, to be subsequently described. The first and second ears 20 and 21 are preferably welded to the member 15 and are of 50 strong metal similar to that of the member 15.

Referring to the sleeve member 25, best shown in FIG. 8, being preferably a short sleeve which may be of iron, steel or other suitable metal or alloy but preferably of steel, open at both ends. This sleeve is of less length, 55 from its upper edge 26 to its lower edge 27, than the distance between the stop means 18 and the first ears 20 and telescopes over the upper portion of the member 15 to slide up and down therealong, limited in its upward movement by the stop means 18 engaging the upper edge 26 and 60 limited in its downward movement by contact of the upper edges of the first ears 20 with the lower edge 27 of the member 25, whereby these ears 20 have dual functions.

65 The member 25 rigidly carries a plurality of third projections, as ears 28, extending radially outwardly from its outer periphery and provided with horizontally-extending axially-aligned openings or bores to receive pivot means as the shanks of bolts 46 to be referred to subsequently.

70 Operatively connected to the members 15 and 25 are a plurality of upwardly-extending support legs or grapple

members 31 of the work support means 30 of the grapple. Each leg or member 31 is preferably one longitudinal half of an elongate cylindrical rod, turned outwardly at its lower end portion to form a foot 32. The flat side face 33 of the leg 31 faces inwardly and the flat face 34 of the foot faces downwardly, with the curved faces 35 and 36 of the leg and foot respectively facing outwardly and upwardly respectively. It will be noted, as in FIG. 4, for example, that the curved faces 35 and 36 of the legs and feet engage the curved surfaces of the work, rather than any sharp edges, while the feet always engage the work or the support E, but the legs may not engage the work (as in FIG. 5).

Carried rigidly by each leg 31 are a pair of projections or ears 37 preferably welded to the upper portion of the flat face 33 and a pair of projections or ears 38 preferably welded to the lower portion of the flat face of the leg. All pairs of ears 37 and 38 have axially aligning openings for pivot pins.

Connection means 40 of the support means 30 between the legs 31 and member 15 preferably comprise a plurality of levers 41, one pivotally connecting each pair of ears 20 and each pair of ears 37, and a plurality of levers 42, one pivotally connecting each pair of ears 21 and ears 38. It is preferred to use the shanks of conventional bolts 43 as pivot pins to extend through aligning openings in the respective pairs of ears and openings in the end portions of the respective levers 41 and 42, with conventional lock nuts 44 screwed upon the projecting screw-threaded ends of the bolt shanks.

Connection means 40 also includes a plurality of links 45, two being pivotally connected at one end portion of each with a projection or ear 28 and an intermediate portion of a lever 41. The shanks of bolts 46 extending through openings in the levers 41 and outer end portions of the links 45, provide pivot pins for the outer end portions of the links. It will be noted, as in FIG. 1, that the longitudinal axes of a lever 41 and lever 42 operatively connected to the same leg 31, are substantially parallel at all times, and that the limits of movement of the member 25 are such that the pivotal connections of links 45 to levers 41 are never at dead centers.

In the forms A and B of the invention, I prefer to provide first coupling means 50 or 50' respectively for coupling a conventional hook and line, as a wire cable (not shown), having a hook at its lower end, to the first member 15 or 15' for effecting expansion of the legs of the grapple. The means 50 is preferably a bail with the lower parts of its legs 51 extending into the slots 17 and welded to the member 15 to project upwardly thereof. The means 50' is like the means 50 and its legs extend into slots, like the slots 17, in the member 15' and welded thereto.

Also, in the forms A and B, I prefer to provide second coupling means 55, as shown in FIGS. 1 and 8, and coupling means 55', as shown in FIGS. 9 and 10 respectively for coupling a second conventional hook and line, as a wire cable (not shown) having a hook at its lower end, to the member 25 or 25', as the case may be, for effecting retraction of the legs of the grapple. In the case of the second member 25, the means 55 is a bail with the lower parts of its legs secured to the upper end portion of the member 25, at its outer periphery, as by welding, to project rigidly thereabove.

In the case of the form B of the invention, the means 55' is a bail 56 with the free end portions of its legs pivotally connected, substantially as shown in FIG. 10, to upwardly extending arms 57 which are rigid with the member 25' to project upwardly therefrom and may be secured, at their lower end portions, as by welding, to the outer periphery of the member 25'. The free end portions of the legs of the bail 56 and the upper free end portions of the arms 57 may be provided with eyes through which may extend pivot pins 58 of any approved form, such as shown in FIG. 10.

5 The means 55' of form B is provided so that the bail 56 may be pivoted downwardly, as in FIG. 9, in order to be out of the way when the bail 50' is in use.

In FIGS. 9 and 10 parts which are preferably exactly like similar parts of form A of the invention are shown by like numerals provided with an exponent (').

In the use of the grapples of forms A and B, if a grapple has its legs expanded and it is desired to retract them for introduction into the opening or openings 60 in a load, as the load C of FIG. 4 or openings 70 in the load D (and opening 71 in the support E) of FIG. 5, the weight of the grapple is placed upon the bail of either the means 55 or 55' by suspending the grapple from a hook (not shown) attached to a taut longitudinally immovable (not shown). This will cause automatic retraction of the legs of the grapple. The grapple may then be lowered into the openings, either 60 or 70, as the case may be.

When the feet of the lowered grapple are in positions so that, when the legs are expanded, the feet will hook under the bead 61 of the lowermost load C or under the platform body 71, the hook under the connection means 55 or 55' is uncoupled. In the case of the grapple of form B, the bail 56, will pivot downwardly, out of the way and, in either case, a hook may be hooked under the bail of the connection means 50 and 50' and the hook, and, with the line attached to the hook under the connection means 50 and 50' and payed in, the feet will come into engagement with the load or support and support the same for raising and carrying the load and, if used, also the support.

Because of the suspension of the load (or load and support E) upon the feet, there will be at least a three-point suspension or, if there are more than three legs and their feet employed, there will be a suspension of more than three points although I have discovered that, while a two-point suspension is not desirable, a three-point suspension is generally adequate for support and tipping-prevention of the load, despite the fact that, in cases, the legs will not engage the walls of the openings in a stacked load, although the feet must extend, at least for parts of their lengths, under the load or the support E.

Economy in construction of the grapples may be effected by dividing a cylindrical rod longitudinally to provide a pair of legs and feet, when the lower ends of the divided rod are turned to project outwardly from the balance of the divided rod. The rounded surfaces thus provided are less apt to damage the loads than would surfaces of other shapes and the substantially flat surfaces or faces 33 of the legs are much more desirable to attach (as by welding) the projections or ears 37 and 38 to the legs 31.

In the construction of the coupling means 50 and 55 or 50' and 55', one being spaced above the other with the longitudinal axis of the members 15 and 25 substantially passing through the uppermost portion of each bail, there is a direct upward pull upon any one of the bails, in contradistinction to pulls transversely of the longitudinal axes of the grapples, since such transverse pulls tend to set a grapple to swaying. I have discovered that, depending wholly on the use of the lines, drawn up or payed out, and gravity, and not depending upon springs, cams or the like, the grapples of my invention will function satisfactory and without being guided by the operator's hands upon the grapples.

Various changes may be made to the forms of the invention herein shown and described without departing from the spirit of the invention or scope of the claim.

What is claimed is:

A lifting and carrying grapple, including an upwardly extending elongate body member, a sleeve member telescoping therewith at the outer face and upper portion thereof; work supporting means, including a plurality of upwardly-extending legs provided with outwardly projecting feet, said legs being spaced from said members 70 a substantially equal distance apart; first set of levers, con-

nected between the intermediate portion of said body member at a location below said sleeve member and the upper portions of said legs; second set of levers connected between the lower portion of said body member and the lower portions of said legs; link connection means pivotally connected between said sleeve member and the intermediate portions of said first set of levers; coupling means carried by said body member to couple said body member to a support; and coupling means carried by said sleeve member to couple said sleeve member to a support, both of said coupling means including a separate

bail, one spaced from the other, with the longitudinal axes of said members extending through the uppermost portion of each bail.
